Fig. 1 is a top plan view of a wall can opener embodying my new design;

Fig. 2 is a side elevational view thereof;

Fig. 3 is an elevational view of the side opposite to that shown in Fig. 2;

Fig. 4 is an end elevational view looking from the left of Fig. 2; and

Fig. 5 is an end elevational view thereof looking from the right of Fig. 2 as it appears with portions of the handle broken away for convenience of illustration.

The broken line illustration of the detachable, magnetic can top holder shown on the drawing in Figs. 1, 3, 4 and 5 is for illustrative purposes only.
